UNITED STATES PATENT OFFICE

FREDERICK C. HEINEN, OF CHICAGO, ILLINOIS

DOOR ELEVATING MEANS

Application filed June 14, 1930. Serial No. 461,116.

This invention relates to doors generally and contemplates more specifically, for application to side slide doors of railway house cars, means for elevating said doors.

It is an object of this invention to provide door elevating means in which an operating handle is employed, said handle being positioned preferably adjacent the vertical edge of a door.

10 A further object is the provision of door elevating means in which unauthorized elevation of a door when in closed, latched position is prevented.

It is an object, also, to associate the operating handle of door elevating means with the usual latching mechanism of the door so that said latching mechanism may be utilized to prevent unauthorized lifting of the door when said mechanism is in operative position.

20 An object resides in the arrangement of door elevating means in which the elevating force is communicated to the door to effect elevation thereof at the remotest point possible consistent with practical considerations.

25 An object, as well, is the provision of a stationary operating handle secured to the door and provided with stop means adapted to limit the movement of door elevating means, whereby a portion of said elevating

30 means and said stationary means may be grasped by the operator to move the door.

Other objects and advantages will become apparent as the description of the invention proceeds, taken in connection with the drawings forming a part of the specification and in which similar numerals refer to similar parts throughout.

In the drawings:

40 Figure 1 is a partial elevation showing the elevating means of the invention applied to a double door construction.

Figure 2 is a sectional view taken on line 2-2 of Figure 1.

45 Figure 3 is a sectional view taken on line 3-3 of Figure 1.

Figure 4 is a partial elevation of the structure shown in Figure 1, illustrating means applied to the elevating means to prevent movement of the latter when the door is in latched position.

Figure 5 is a sectional view taken on line 5-5 of Figure 4.

Figures 6, 7 and 8 are views similar to that shown in Figure 1, illustrating modifications of the invention.

55 Figure 9 is a sectional view taken on line 9-9 of Figure 7.

Figure 10 is a view similar to Figure 4, showing modified means for preventing movement of the elevating means applied to a single door construction.

Referring to the form of the invention illustrated in Figures 1 to 3, inclusive, the numerals 10, 10 designate car doors which, in this instance, are shown arranged in pairs 65 for double door house cars and which are adapted to be supported for rolling movement upon the rolling elements 11, here indicated as balls, mounted for movement in runways 12 carried by the doors and upon 70 a track member 13. The track may be secured to the underframing of the car by the customary brackets (not shown). In its lowered position the door is adapted to be supported directly upon the track 13 by means 75 of pads 14 carried by brackets 15, 15' secured, as by rivets, to the lower corners of the doors.

In order to elevate the door from its position upon the track and to support the door 80 directly upon the rolling elements for movement in opening or closing direction, door elevating means has been provided. The elevating means comprises the runways 12 formed preferably of angle members 16 and 85 17, positioned with two of their corresponding legs in abutting relation and riveted together through said legs. In the ends of each of the runways is positioned and fastened a bracket member 18, preferably in the form of a casting. The bracket member is provided with a trunnion 19 positioned eccentrically relative to the runway and adapted to be received in a bearing 20 formed in the bracket 15' or in a corresponding bearing 90 formed in the bracket 15. Each bracket member 18 is also provided with a depending lug 21, adapted to contact with its corresponding pad 14 to limit the transverse rotational movement of the runway 12 about the 100

rolling elements 11 as fulcrums in the elevation of the door. The lug adjacent the forward edge of the door co-acts with an operating lever 22 to transmit the force applied to said lever to the runway to effect rotational movement thereof in order to elevate the door. The lever 22 is provided with a cam portion 23, adapted to contact with the lug 21 and with a handle 24 by which the lever may be conveniently operated. The lever is mounted for pivotal movement in a plane parallel to the door upon a hub 25 provided on the casting 15'.
5

Secured to the door 10 is a stationary handle 26 provided with a projection 27 positioned slightly above the handle 26 and with which the lever 22 is adapted to contact when a downward pull is exerted thereon, to elevate the door. The projection 27 thus supplements the lug 21 in assuring a positive limit of rotational movement of the runway 12.
10

In order to prevent tampering with the elevating mechanism and to avoid raising the door when the latter is in latched operative position it is desirable to secure the operating levers 22 against movement. A construction for accomplishing this beneficial result is illustrated in Figure 4 of the drawings. In this form each of the levers 22 is provided with a lobe 28 to which is pivoted one end of a link 29. The link on the right hand or main door is provided with a pair of spaced projections 30, 30 and the link on the left hand or auxiliary door is provided with only one projection adjacent the upper end of the link. Secured to the right hand door is a hasp fastener 31 on which is pivotally mounted a hasp 32 adapted to be secured to the left hand door when both doors are closed by the usual pin and staple arrangement carried by a bracket 33 secured to the left hand door. The links 29 are adapted to lie between the doors and the hasp 32 with the extensions 30 adjacent the upper end of said links lying upon said hasp. It is apparent that in this position with the doors closed and sealed, downward movement of the levers 22 is prevented.
20

50 A lug 34 is provided on each of the castings 15' secured to the doors. This lug is adapted to control the movement of its associated link 29 through contact therewith and, referring to the right hand door, the link 29 will in turn, by means of the projections 30 on said link, control the movement of the hasp 32 when the latter is released in order to open the doors. Upon its release the hasp will move downwardly about its pivotal connection with the hasp fastener 31 and lie between the projections 30. In this position of the hasp it will clear the lug 34, which is beveled for this purpose. The doors may then be opened to any desired extent by a downward pull on the levers 22. When the
60
65

doors are closed and the levers released the latter will move upwardly. During this upward movement the links 29 will also move upwardly under the control of the lugs 34 and, in view of the fact that the hasp 32 lies between the projections 30 of the right hand link 29, said hasp will also be guided toward operative position. It is to be noted that the lugs 34 will effect a progressive change in the angular relation of the links 29 relative to the levers 22 so that at no time during the downward or upward movement of the levers will the links extend beyond the adjacent edge of their respective doors. By this arrangement damage to the links is avoided.
70
75
80
85

In Figure 6 there is illustrated a modified lever construction which, however, incorporates an arrangement preventing operation of said levers when the doors are latched in their home position. In this construction the links 29 are dispensed with and the levers 35, 35 are arranged substantially vertical to lie between the hasp 32 and the doors. In this modification there is shown also operating levers positioned adjacent the rear edges of the doors. The operating levers are adapted to operate in a plane parallel to the doors.
90
95

Figures 7 and 9 illustrate a modified door elevating construction. In this modification the elevating means includes the runway 12 eccentrically connected to the door adjacent its ends. In addition thereto the door 10 has rigidly secured to it a member 36, preferably in the form of a casting or forging, to which an operating lever 37 is pivotally attached. The casting or forging is shown positioned substantially centrally of the door but it is to be observed that the handle 37 extends to a point adjacent the forward edge of the door. The member 36 is provided with a pad 38 which rests upon the track when the door is lowered. Carried by the runway 12, either by means of riveting as shown, by welding or by an integral formation is an outwardly extending lobe 39, the upper surface of which is preferably rounded and which is adapted to transmit the downward pressure of the handle 37 into a rotational movement of the runway to elevate the door. It is apparent, in this modification, that the lever operates in a plane parallel to the door and that, if desired, the stationary handle 26 may readily be employed with the lever 37 in the manner set forth in the description of Figures 1 to 3, inclusive, of the drawings. It is to be noted also that by transposing the castings 36, together with their levers 37, and lobes 39 from one door to the other these castings may, without change, be positioned adjacent the lower corners of the doors while avoiding the undesirable feature of having the
100

110
115
120
125
130
135

levers extending beyond the forward edges of the doors.

In Figure 8 an extension similar to that shown in Figure 6 is illustrated applied to operating levers 40, 40 rigidly secured to the runways 12 and designed to effect elevation of the doors by an outward pull rather than by movement in a plane parallel to the door. It is to be noted that by offsetting the levers as shown at 41, 41 they may be made to extend and be latched behind the hasp 32.

A further modified latching arrangement for an operating lever, capable of movement in a plane parallel to the door, is shown in Figure 10 applied in this instance to a single door house car construction. A lever 42 is provided preferably cast integrally therewith with a lug 43. A bracket 44 secured to the door carries a lug 45 provided with an opening aligned with an opening formed in the lug 43, together with a staple 46. In order to secure the lever 42 it is only necessary to swing the hasp 47 so that the staple 46 extends through an opening therein and to pass the locking pin 48 through the aligned openings in the lugs 43 and 45 and in the staple. The pin may then be sealed as shown at 49.

The operation of the elevating means of the invention is believed clear from the foregoing detailed description. When the operating lever is pulled downward the cam portion 23 of the lever forces the lug 21 downwardly, producing a transverse rotation of the runway 12 about the rolling elements 11 as fulcrums. In this rotational movement of the runways the doors will be elevated by the eccentric connection between the runways and the doors provided by the trunnion 19 on the member 18 secured to the runway and the bearing 20 formed in the bracket 15 secured to the door. This mode of operation remains the same with each form of operating lever disclosed.

It is to be understood that the door elevating means may be used either with double doors of house cars or with single doors therefor and that the doors shown are merely for the purpose of illustration and are not to be construed in any manner as limiting.

It is evident that many changes in details may be made without departing from the spirit of the invention as defined by the claims appended hereto.

I claim:

1. In combination, a door, a runway eccentrically connected to said door, said door and said runway being capable of relative vertical movement, a track, rolling elements seated within said runway and supported upon said track, said door normally resting upon said track and means adapted to rotate said runway to raise said door about its connection with the runway, whereby said door is supported for movement upon the rolling

elements, said means comprising a lug depending from said runway and a lever carried by said door.

2. Elevating structure for a car door, comprising a member, eccentric connection between said door and said member, bracket means carried by said member, said bracket means having a lug extending therefrom, and a lever pivotally carried by said door and adapted to coact with said lug to rotate said member. 70

3. Elevating mechanism for a car door comprising a member eccentrically and rotatably connected to said door, a lug extending from said member, an operating lever pivotally attached to the door, said lever being engageable with said lug for rotating said member and lifting the door, and means on said door contacting with said lug to limit rotation of said member. 80

4. Elevating means for a car door comprising, a member pivoted eccentrically to said door, a lug depending from said member, and a lever pivotally supported upon said door adjacent a vertical edge thereof and engageable with said lug to impart movement to said member. 90

5. In combination a lift door, latching mechanism for said door and means for elevating said door having a portion engageable by said latch mechanism when the door is in closed position to prevent lifting of the door. 95

6. In combination, a lift door, a latching device for said door and mechanism for elevating said door, said mechanism comprising lever means having a portion engageable by said latching device when the door is latched to prevent lifting of said door. 100

7. In combination, a lift door, a latching device for said door and means for elevating said door, said means embodying a link adapted for engagement with said latching device to prevent lifting of said door. 105

8. In combination, a lift door, a latching device for said door, means for elevating said door, said means embodying a pivoted link and a lug on said link, said lug having engagement with said latching device to prevent lifting of said door. 110

9. In combination, a lift door, elevating means therefor, latching mechanism for said door, said latching mechanism comprising a hasp member, a portion of said elevating means being engageable by said hasp member to prevent lifting of the door. 115

10. In combination, a lift door, elevating means therefor, a latching device including a hasp for said door, said means embodying a pivoted link provided with a lug, said link extending between said door and said hasp with the lug in engagement with said hasp whereby lifting of the door is prevented. 120

11. In combination, a lift door, a latching device for said door, said device comprising 125

a hasp member, means for elevating said door, said means comprising a lever and a link pivotally connected to said lever, a lug on said link adjacent one end thereof, said link extending between said door and said hasp 5 with the lug resting upon said hasp whereby lifting of the door is prevented.

12. In combination, a lift door, latching mechanism for said door, means for elevating said door, said means embodying a link pivotally connected thereto, said link being engageable with said latching mechanism, said link being positioned substantially at a vertical edge of the door, means carried by said door and engaging said link, whereby in the 15 lowering movement of the door said link will be maintained by said lug within the vertical edge of the door.

13. In combination, a lift door, a latching device for said door, means for lifting said door, said means comprising an operating lever, a link pivotally connected to said lever, one end of said link extending normally beyond a vertical edge of the door, said link 25 being engageable with said latching device to prevent lifting of the door, and a lug carried by said door for guiding said link to engageable position with said device during the lowering of said door and for maintaining said link within said vertical edge 30 of the door during the movement of the link.

14. In combination, a lift door, a latching device for said door, said device including a pivoted hasp, elevating means for said door, 35 said means embodying a pivoted link, a pair of spaced lugs on said link, said hasp lying between said lugs when said door is latched or unlatched.

15. In combination, a lift door, latching 40 mechanism including a pivoted hasp for said door, elevating means for said door, said means embodying a pivoted link, a pair of spaced lugs provided on said link, said hasp being adapted for contact with one of said 45 lugs when the door is in unlatched position, means carried by said door for controlling the movement of said link in the lowering movement of the door, said hasp being guided toward latching position during the 50 movement of said link.

Signed at Chicago, Illinois, this 11th day of June, 1930.

FREDERICK C. HEINEN.
